UNITED STATES PATENT OFFICE.

CHARLES D. BEHAN, OF STIGLER, OKLAHOMA.

WELL-BUCKET.

1,342,414.

Specification of Letters Patent.

Patented June 8, 1920.

Application filed January 22, 1920. Serial No. 353,287.

To all whom it may concern:

Be it known that I, CHARLES D. BEHAN, a citizen of the United States, and a resident of Stigler, in the county of Haskell and State of Oklahoma, have invented certain new and useful Improvements in Well-Buckets, of which the following is a specification.

My invention is an improvement in well buckets, and has for its object to provide a bucket of the character specified especially adapted for use in wells of small diameter, as, for instance, cased wells, for permitting the bucket to fill from the bottom without the necessity for tilting the same, and to empty in the same manner when at the top of the well.

In the drawings:

Figure 1 is a front view of the improved bucket;

Fig. 2 is a vertical section;

Fig. 3 is a section on the line 3—3 of Fig. 2;

Fig. 4 is a vertical section of another embodiment of the invention.

In the embodiment of the invention shown in Figs. 1, 2 and 3, the improved bucket comprises a cylindrical casing 1 having its ends open and provided with transverse partitions 2 and 3 near its ends.

A suitable bail, indicated at 4, is connected with the top of the casing, and the partition 3 has a central depending nipple 5, which forms a portion of a water seal. A cup 6 is arranged directly below the nipple, being supported by a cross bar 7, and the lower end of the nipple dips into the cup, being below the surface of the water in the cup.

A suitable substantially U-shaped pipe is arranged within the casing, the said pipe comprising a body 8 and arms 9 and 10. The body 8 of the pipe is arranged below the partition 3 and the arms 9 and 10 extend upwardly through openings in the partition 3 and through openings in the partition 2, the pipe 10 having a return portion 11 at its upper end which again passes downwardly through the partition 2, so that the arm 10 of the pipe opens between the partitions 2 and 3, while the arm 9 opens above the partition 2.

Within the body of the pipe 8 and within the arm 9 and extending slightly within the arm 10 at its lower end there is arranged a pipe 12, this pipe being of less diameter than the pipe 8—10, so that there is some

space between the said pipes. The outlet end of this pipe 12 extends upwardly into the arm 10 of the pipe 8, 9 and 10 a slight distance, stopping short of the bottom of the cup 6, and at the arm 9 the pipe 12 extends to the upper end of the said arm and is provided with a compressible bulb 13 at the said end.

65

The improved bucket in each form shown is valveless, water seals being substituted for valves, and when the bucket is full it can be emptied only through the admission of air.

In the use of the bucket shown in Figs. 1, 2 and 3, it is lowered into the well, and as it passes into the water in the well the water will pass up through the opening between the cup and nipple and will fill the body of the bucket. When the bucket is raised the water seal will prevent the outflow of the water, and the atmospheric pressure will hold the water in the bucket and will prevent its breaking the seal. Air must be admitted to the body of the bucket before water can flow, and the air is admitted by means of the pipes 8—9—10—12. When it is desired to empty the bucket pressure is made upon the bulb 13 and this forces air through the pipe 12 into the ascending arm 10 of the pipe 8—9—10.

75

When the bucket is filled the pipe 8—9—10 also fills, thus forming a water seal against the entrance of air at the body of the said pipe 8. A valve, indicated generally at 14, 90 is provided in the body 8 of the pipe 8—9—10 and a valve, indicated at 15, is provided at the junction of the portion 11 with the arm 10. When either of these valves is opened air is admitted to the body of the bucket, and the atmospheric pressure no longer prevents the outflow of water.

85

As shown, a cord or wire 16 is connected with the valve 14 for operating the same, and, if desired, a branch 17 may connect this cord or wire to the valve 15 so that the valves will be simultaneously operated. With this construction either the valve 14 or the valve 15 may be used to empty the bucket, or the bulb 13 may be used. When the valve 14 is opened the water drains out of the pipe 8—9—10 and air enters freely, thus equalizing the pressure in the bucket so that the water may flow out. When the valve 15 is open the air flows into the top of the bucket and the procedure set forth follows. When air is injected into the arm 10 of the pipe 8—9—10 by the bulb 13 the atmospheric pressure is broken.

95

100

105

110

In the embodiment of the invention shown in Fig. 4 the bucket comprises the cylindrical casing 18 corresponding to the casing 1 of Fig. 1, and having the bail 19. Partitions 20 and 21 are arranged transversely of the casing near its ends, the partition 21 having the central nipple 22 which dips into the cup 23 supported by the brackets 24 and forming a water seal. A siphon shaped pipe, consisting of legs 25 and 26, is arranged within the casing, the junction between the legs dipping through the nipple 22 to near the bottom thereof. The leg 26 terminates near the partition 20 and below the same, while the leg 25 extends through the said partition.

A tube 27 extends through the leg 25 and through the junction between the legs and for a short distance into the leg 26, terminating above the partition 21. This tube has a bulb 28 for injecting air into the leg 26. When the bucket is filled and lifted the atmospheric pressure will hold the contents in the bucket. To relieve this pressure air 25 is injected into the body of the bucket by the bulb 28. This starts the flow of air through the pipes 25 and 26, and the water flows out freely. If desired, a valve 29 may be placed in the partition 20 and when this 30 valve is opened the same result obtains, air entering, thus relieving the pressure on the water in the bucket.

It will be understood that the compression bulb is not necessarily placed at the end of the pipe 12 in Fig. 2, nor at the end of the pipe 27 in Fig. 4. It can also be placed on the end of the pipe 9 in Fig. 2 and on the end of the pipe 25 in Fig. 4. After these bulbs are so placed a hole is cut in the top, 40 of the same diameter as the pipe they cover, to let air escape. To empty the bucket the bulbs are placed over the said holes and compressed, and the bucket empties itself. This arrangement will eliminate the use of the pipe 12 in Fig. 2 and the pipe 27 in Fig. 4. When the bucket is filling the air escapes through these pipes.

I claim:

1. A bucket of the character specified comprising a cylindrical body closed at its top and having an opening in its bottom, a water seal for closing the said opening to retain the water in the bucket by atmospheric pressure, means for admitting air to the bucket to discharge the water, said water seal comprising a cup supported in the body, said bucket having at the opening in its bottom a nipple depending into the cup, the means for admitting air comprising a siphon shaped pipe having one arm extending out at the top of the bucket and another arm opening into the bucket near its top, and a pipe extending through the first named arm into the other arm and having a bulb at its 65 outer end.

2. A bucket of the character specified comprising a cylindrical body closed at its top and having an opening in its bottom, a water seal for closing the said opening to retain the water in the bucket by atmospheric pressure, and means for admitting air to the bucket to discharge the water, said water seal comprising a cup supported in the body, said bucket having at the opening in its bottom a nipple depending into the cup, the means for admitting air comprising a siphon shaped pipe having one arm extending out at the top of the bucket and another arm opening into the bucket near its top. 80

3. A bucket of the character specified comprising a cylindrical body closed at its top and having an opening in its bottom, a water seal for closing the said opening to retain the water in the bucket by atmospheric pressure, and means for admitting air to the bucket to discharge the water, the means for admitting air to the bucket comprising a siphon shaped pipe having one arm extending out at the top of the bucket and another arm opening into the bucket near its top. 85

4. A bucket of the character specified comprising a cylindrical body closed at its top and having an opening in its bottom, a water seal for closing the said opening to retain the water in the bucket by atmospheric pressure, and means for admitting air to the bucket to discharge the water, said water seal comprising a cup supported in the body, 95 said bucket having at the opening in its bottom a nipple depending into the cup. 100

5. A bucket of the character specified comprising a cylindrical body closed at its top and having an opening in its bottom, a water seal for closing the said opening to retain the water in the bucket by atmospheric pressure, and means for admitting air to the bucket to discharge the water, the means for admitting air comprising a valve in the top 110 of the bucket, the bottom of the bucket having a valve. 105

6. A bucket of the character specified comprising a cylindrical body closed at its top and having an opening in its bottom, a water seal for closing the said opening to retain the water in the bucket by atmospheric pressure, and means for admitting air to the bucket to discharge the water, the means for admitting air comprising a valve in the top 115 of the bucket. 120

7. A bucket of the character specified comprising a cylindrical body closed at its top and having an opening in its bottom, a water seal for closing the said opening to retain the water in the bucket by atmospheric pressure, and means for admitting air to the bucket to discharge the water. 125

CHARLES D. BEHAN.
